A specimen of such industry is designated by the term "paper folding," and it is well known that such a process, if not properly conducted, is apt to result in a product which is not only unsightly but incapable of performance. A further and improved process has been devised which is not only more effective but also more economical. The present invention is directed to a process of preparing a continuous web of paper which is not only more effective but also more economical. The present invention is directed to a process of preparing a continuous web of paper which is not only more effective but also more economical.

UNITED STATES PATENT OFFICE

SUPERFOLDED PAPER TAPE

Leslie T. Hand, Brooklyn, N. Y.

Original application January 28, 1933, Serial No.

654,000. Divided and this application December

8, 1933, Serial No. 701,463

(Cl. 281—5)

My invention is a novel development of prepared paper supply for use in machines consuming paper, such as adding machines, calculating machines, stock tickers, tape recorders, teletype writers, and the like. Heretofore all these machines used a prepared paper supply in roll form as there was no other suitable product. The folded paper which has been developed prior to my product was not perfectly aligned; nor was it of sufficient, continuous, uninterrupted length.

The known product of the small roll industry will be referred to hereinafter as a rewound roll. The new product which has been developed by me will be referred to as superfolded paper. Rewound rolls are made and used under names such as adding machine rolls, stock ticker rolls, teletype rolls and the like. Superfolded paper can be used in place of these products at great saving and with many new conveniences to the consumer.

The invention of superfolded paper offers a new product which will increase the effectiveness of many recording devices and widen their field.

The machines mentioned above require a paper supply which will provide the maximum length of uninterrupted paper web compacted into the available space for such supply. Rewound rolls do just this but present certain limitations.

A rewound roll grows in diameter and weight as the length of paper web on the roll is increased. The heavier the roll the greater the force required to start the feeding of the paper web. After overcoming the inertia retarding the start, much less force is required to keep the roll going due to the momentum of the moving roll. With the intermittent operation of most of these machines, they are restricted to a rewound roll of comparatively small diameter.

In 1926 the problem was presented of designing a paper supply which would provide ten thousand feet of paper web in a continuous, uninterrupted strip. A rewound roll containing this length of web was readily obtained, but was of such great diameter and of such great weight that it was wholly unsuitable. Not the least of its drawbacks was the fact that it decreased in weight and diameter as the supply was consumed.

The present inventor canvassed all known methods of folding paper, known as fan folding,

zigzag folding, continuous folding, and the like, but could find no method of producing a product which was compactly folded, of sufficient length (even equaling the amount only of web in a rewound roll of small diameter) and of a continuous

precipitately broken or cut on the edges, nor transversely across the web. Small packs of folded paper, made by known methods, were pasted together, and machine and method patents were issued with the Numbers 1,718,743, June 25, 1929, and 1,747,719, February 18, 1930.

The product derived by so attaching a multiplicity of folded packs was not satisfactory. Rewound rolls were perfectly aligned along the edges and the web was the same width throughout its length. The folded paper was not. All kinds of expedients were used to make the folded paper work satisfactorily, but without success, over a period of five years. To perforate the folds, or to otherwise weaken them to any extent would destroy the usability of the product for its purpose as recording tape.

Rewound rolls are made up with one or more webs of paper and the new product, superfolded paper, is also understood to include one or more webs of paper.

At a later date experiments were completed for the production of superfolded paper. This new product was of great length, closely compacted, with uninterrupted web, and perfectly aligned along the edges. The machinery for producing the product was perfected and application for Letters Patent was filed January 28, 1933, with Serial No. 654,000. The present application is a division thereof.

My new product of superfolded paper may be produced as by the machine illustrated and described in my said original application, Serial No. 654,000, or by other suitable means, and such portions of the drawings in said original application as are necessary to illustrate a practical means of producing superfolded paper are given in this application, to facilitate an understanding of the new product.

Other features and advantages of my invention will hereinafter appear.

In the drawings:

Fig. 1 is a side elevation of a machine embodying my improved means for the stacking of plies of web upon a table that is manually adjustable as to its height, and including means for non-separately slitting the web into tape widths.

Fig. 2 is a perspective view of web fold compacting means, and

Fig. 3 is a perspective elevation of a stack of superfolded paper, non-separately slitted into tape widths, and showing a stack of superfolded tape separated from said main stack.

Describing first the mechanism disclosed in Fig.

1, let 1 indicate the machine base, which may be in the form of parallel, spaced members bearing that numeral, and let 2 indicate a frame composed of vertical members forming a rectangle, 5 the upper part of said frame having its vertical members connected by the horizontal beam members 3.

As in Patent No. 1,747,719 shafts 4, 5, are journaled in bearings mounted on the beams 3, said 10 shafts carrying the rollers 6, 7 that are disposed in horizontal parallelism, their opposed surfaces being in juxtaposed relation and adapted for the passage therebetween of the web 8 which is supplied thereto from a source as will be described 15 hereinafter.

The rollers 6, 7 are provided with web indenting means, not herein shown, and are rotated oppositely by the intermeshing gears 10, 11, the drive means being by way of a pulley wheel 12 20 that is driven by a belt 13 as from a motor 14, said pulley wheel being shown as having a pinion 15 that is in mesh with the gear 10, all these elements being found in Patent No. 1,747,719.

One of the novel elements comprised in this invention consists in means for adjusting the height of the stack supporting table 16, which table is located beneath the rollers 6, 7 and positioned in spaced relation therefrom suitable for the indented folds of the web leaving said rollers to fall 25 upon its surface. Obviously as a stack composed of web plies grows upon the table the space separating the upper surface of the stack and rollers 6, 7 diminishes, and therefore it becomes necessary to lower the table in order to maintain the 30 same spacing relation. To this end I have shown table 16 as carried by guide members 17 that are slidable upon vertical members 18 secured at opposite sides of the frame. The table is supported by flexible connectors, here shown as sprocket 35 chains 19 engaged with the table at opposite sides thereof, these chains being passed over idlers 20, and sprocket wheels 21 carried by a shaft 22 that is mounted on the frame, said chains depending below sprockets 21. As means for operating the 40 sprockets 21 and chains 19 I provide a sprocket 23 which is mounted on a frame member 2 beneath one of the sprockets 21, and the chain 19 which is passed over said sprocket, is carried beneath it in order that it may be passed over 45 sprocket 23 and engaged therewith, so that the rotation of sprocket 23 will initiate the movement of the chains and hence control the vertical travel of the table. Whilst as stated the chains at one end are pendent, they are connected at 50 their other ends to the table as by means of eye-bolts 24 or the like secured to the table.

Means for rotating the sprocket 23, including an operating handle 28, to raise and lower the 55 table, are illustrated in original application Serial No. 654,000.

Also, as shown in Fig. 1, the machine base is extended forwardly and supports a standard 29, having a bracket 30 that carries a spool 31 upon which the web of paper 8, of suitable width and considerable length, is wound, this web passing from the spool, around an idle roller 32, and being guided by way of a roller 33 to an advanced web engaging roller 34, whose forward surface presents the web to the slitting action of a circular knife 53. The web leaving the roller 34 passes under a roller 36 and then passes to a more rearward roller 37, over whose surface it depends in a loop 8', whose upwardly directed portion is carried over idlers 38, journaled in fixed standards 39, and thence passes over an

idler 40 journaled in vertical frame members 2, whence it passes to a roller 41, to be thus vertically positioned for passing between the rollers 6, 7.

Resting upon the web 8, above roller 37 is a roller 42, which is journaled in links 43 that are pivoted to the frame uprights 39, whereby said roller imposes its weight against the web, thereby supplying sufficient tension at this point to exert the draft upon spool 31. Also a weight in the form of a roll 44 is placed in the loop 8' to further tension the web in its passage to the point of its gripped engagement between the rollers 6, 7.

The means for feeding the web 8 to the rollers 6, 7 are here shown for example as comprising these instrumentalities: The shaft 45 which carries the roller 34 also carries a pulley 46, which latter is connected, as by a belt 47, with a pulley 48 that is carried by a shaft 49, suitably journaled to the frame 29, said shaft 49 also carrying a sprocket wheel 50 which is engaged by a sprocket chain 51 and said chain also engages a sprocket wheel 52 that is revoluble with the roller 41. Hence, the roller 34 aids the feed movement of the web, and itself receives motion from the motor 14 through the intermediary train referred to. Pulleys A and B, which are connected by a belt C, actually initiate the feed movement of the web, as pulley A is fixed on shaft 45, this transmission being effected by reason of the gripping action of roller 42 on roller 37.

It having been found desirable to slit the web into narrow or tapelike widths in the process of feeding the web to the place where it is to be given folds and piled in plies upon the table, whilst maintaining the integrated width of said web, therefore I employ cutting means in the form of the circular knives 53, mounted in suitably spaced relation and adapted to be held opposed to the roller 34, in contacting relation with the web passing thereover, so that said knives will slit the web whilst they are caused to rotate by such contact.

In order that the slit web may not have the thus formed tape widths separated from the web each knife 53 is provided with a nick in its edge to thereby leave a series of connecting links 54 (see Fig. 3) that unite the tape widths in the web, but whose connecting hold is so slight that piles of tape may readily be detached from a formed stack of web plies.

The detail views of the knives 53, together with the supporting and operating mechanism, are not herein reproduced, as they are fully shown and described in the original application, Serial No. 654,000.

As means for compacting the folds of web forming the stack I provide for each stack a pair of helicoidal members 126, (see Fig. 2), disposed respectively at opposite ends of the plies, and adapted to engage the falling folds, in succession, to press them upon the stack.

These helicoidal members, which are composed of stiff wire, each has its ends 127 bent to lie in a common vertical axis through the member, said ends respectively being suitably journaled so that each member may rotate about a vertical axis. The members 126 of the pair are caused to be rotated oppositely, turning in the directions indicated by the arrows in Fig. 2.

The driving means and all other details of the helicoidal members are fully shown and described in the original application, Serial No. 654,000.

Due to the positioning of the helicoidal members, in pairs, at opposite sides of, and above the stack of web plies, it will be apparent that a fold of the web in falling toward the stack alights first on an upper coil of its adjacent helicoidal member, and said member, in rotating, worms the fold downwardly until said fold is brought under the lowermost convolution, which presses or compacts it on the top of the stack to which it is added.

In the view of a stack of folded web shown in Fig. 3 the lines Y indicate the slits produced therein by the circular knives 53, and at 54 there appear the slight connections left in the web by the nick with which each knife is provided.

The art as previously known included no means for severing tape widths from wider widths of web, and, as a matter of fact it has not been found practicable to cut through a stack of folded plies of paper web of more than three inches in height in attempting to produce stacks of folded tape.

Nor was it heretofore possible to create stacks of continuous tape, because a web of tape width if allowed to fall in folds in an attempt to build a stack thereof, would be uncontrollable so far as previously existing mechanisms are concerned. Therefore it has remained for me to slit the paper web into tape widths, without separation, whilst the web is passing through the folding and stacking machine, leaving the tape connections of so

slight a character that stacks of tape can readily be broken apart from a web stack of relatively great height.

The slight and insignificant edge projections left upon a compacted stack of paper tape that has been broken away from a main stack of paper web are easily removable by brushing.

Variations within the spirit and scope of my invention are equally comprehended by the foregoing disclosure.

I claim:

1. The method of producing stacks of folded paper tape from a web of paper which consists in partially slitting the web into tape widths during passage from a web source to a receiving support, guiding the web in its passage, indenting said web to create folds therein, causing the folded plies to fall successively upon the support to form a stack of partially slit continuous web, and compacting the folds to provide a hard, edge-wise surface on all four sides of the stack.

2. The new product which consists of a stack of continuous, uninterrupted, partially slit paper web, for separation into tape widths, said web having zigzag folds of equal length and being approximately in the form of a rectangular block, the edges of all the folds being in perfect alignment, and said folds being compacted together to provide a hard, edge-wise surface, on all sides of the block.

LESLIE T. HAND.
